HAIR REMOVING DEVICE

Louise L. Magnus, Chicago, Ill.

Application August 18, 1948, Serial No. 44,950

10 Claims. (Cl. 128—355)

1

The present invention relates to a novel hair removing device for the quick and effective removal or extraction of superfluous or unwanted hairs from the face, arms or legs of the body, and to a novel means and manner of removing such hair.

An important object of the present invention is the provision of a novel manually or mechanically operated means and mechanism for the removal of superfluous hairs from any desired portion of the body.

The present invention further comprehends a novel combination and assembly of rollers and adhesive tape so constructed and arranged as to quickly, conveniently and positively remove unwanted hairs from the arms, legs, eyebrows or other portions of the face.

Another important object is to provide a novel hair remover requiring but a single roll or coil of adhesive tape that may be reused and in which device is provided a pair of rollers for the tape, one operating as a feed or supply roller and the other as a take-up roller, but these rollers being reversible whereby the tape may be used and reused so long as it is capable of functioning to accomplish the desired result.

A further important object of the present invention is the provision of a novel construction and arrangement of operating rolls, one of which is loose and over which the tape is drawn and which is in contiguous relation with one or more fixed rolls whereby the hairs are engaged and adhere to the exposed adhesive surface of the tape and are then drawn and clamped between the loose and contiguous rolls and removed by a quick jerk or pull.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while there is shown therein a preferred embodiment, it is to be understood that the same is susceptible of modification and change, and comprehends other details, arrangements of parts, features and constructions without departing from the spirit of the invention.

In the drawing:

Figure 1 is a view in front elevation of the novel hair removing device.

2

Fig. 2 is a view in side elevation thereof.

Fig. 3 is a fragmentary enlarged view in vertical cross section of the hair removal end or portion of the device, the view being taken on the line 3—3 of Fig. 1.

Fig. 4 is a view in vertical cross section taken in a plane represented by the line 4—4 of Fig. 1.

Fig. 5 is a fragmentary, disassembled view 10 showing in vertical cross section one of the rollers operating as a take-up roller and in front or end elevation the detachable operating knob and stub shaft, and which disclose the manner of detachably connecting these members.

Fig. 6 is a fragmentary view part in vertical cross section and part in front or end elevation and showing another form of connection between a take-up roller and the stub shaft on the knob for detachably connecting these parts.

Fig. 7 is a top plan view of an alternate construction of hair remover, a portion thereof being broken away to more clearly show the actuating mechanism.

Fig. 8 is a view in side elevation of the device of Fig. 7.

25 Referring more particularly to the novel illustrative embodiment disclosed in Figs. 1 to 5 inclusive, the hair remover therein shown comprises a frame or support consisting of spaced plates 1 and 2 and a connector 3, the latter being disposed between and spanning the opposite plates whereby to support and mount the latter thereon by means of rivets or other securing means 4. This connector is preferably in the form of a solid section of bar stock having its forward end 5 rounded and so disposed as to provide a guide surface over which rides the rear or untreated side of a roll or coil of tape 6.

30 Rotatably mounted in the opposite side plates 1 and 2 of the frame is a pair of rollers 7 and 8, one operating as a feed or supply roller 7 and the other as a take-up roller 8, each having its opposite reduced ends 9 freely journalled or rotatably mounted in the spaced plates 1 and 2. Due to the present novel construction and arrangement, either roller may be employed as the feed or supply roller to supply the strip or coil of adhesive tape 6 to a pair of relatively closely spaced rotatable members or rolls 11 and 12 having their reduced ends 13 journalled or rotatably mounted in the forward and reduced ends 14 of the spaced plates 1 and 2. Tape from the feed or supply roller is fed between one of these rolls and over a loose or floating pin or roller 15 disposed somewhat forwardly of and intermediate the rolls 11 and 12, and back between this loose

or floating pin or roll 15 and the other of these rolls. The floating pin or roll 15 is free of and its ends spaced inwardly from the side plates 1 and 2 (see dotted lines in Fig. 1) and movable relative to these side plates and to the rolls 11 and 12 journalled in the side plates, and applies tension to the tape at either side thereof, depending upon which of the rollers 7 or 8 is the feed or supply roller and which is the take-up roller.

To operate the device and assuming the roller 8 is the take-up roller and an end of the tape from the feed or supply roller 7 has been fed between the rolls 11, 12 and 15 and attached to the take-up roller 8, a knob 16 having a stub shaft 17 is attached to the roller 8 for rotating the latter to withdraw tape from the feed or supply roller 7. To provide for such detachable connection, the stub shaft 17 is of such length as to extend but part way into the hollow rollers 7 and 8, and is provided with a slotted end 18 adapted to engage a cross pin 19 in the hollow rollers whereby when the slotted end is aligned with the cross pin, the latter enters the slot and rotation of the knob 16 and the stub shaft 17 is transmitted to the pin 19 and its roller.

Fig. 6 shows an alternate manner of detachably connecting the knob to either of the rollers 7 or 8 for rotating these members and the tape 6. In this form, a squared or polygonal stub shaft 21 is attached to the knob and adapted to be conformably received in a complementary opening 22 in the rollers 7 and 8. In either form of the detachable connection, either the roller 7 or the roller 8 may be the supply or feed roller and the other the take-up roller, whereby the tape may be moved in either direction and reused over and over again.

In Figs. 7 and 8 there is disclosed an alternate construction of hair remover comprising a frame or housing 23 having a top plate 24 and downwardly projecting side plates 25 and 26. The top plate at its forward end 27 is flared downwardly and outwardly to provide a guard or guide to separate the hairs that are to remain from those to be removed. This structure is particularly applicable to the arching or removal of unwanted hairs from the eyebrows. Like the preceding form shown in Figs. 1 to 4 inclusive, a pair of rollers 28 and 29 are provided, the upper roller 28 being the supply or feed roller and the lower roller 29 the take-up roller. As shown in Fig. 8, the upper roller 28 is illustrated as initially receiving the tape 30 with the end of the tape being fed or passed under an upper roll 31 rotatably mounted in the frame or housing by having its opposite ends journalled in the opposite side plates 25 and 26. The end of the tape is then fed or passed over a floating or loose roll 32 which is free of and spaced inwardly of the side plates 25 and 26 and over the lower roll 33 having its ends journalled in the opposite side plates 25 and 26 in the same manner as roll 31. Thus the rolls 31 and 33 are rotatably mounted in the frame in spaced relation and the loose or floating roll 32 is disposed between and somewhat forwardly of the rolls 31 and 33 in the manner shown in Figs. 2, 4 and 8.

In either form of the invention, after the roll of tape has been wholly or partially used or exhausted from the feed or supply roller, the knob and its stub shaft are removed from the opening in the take-up roller and inserted into the opening of the roller that was previously the feed or supply roller, whereupon the latter roller func-

tions as the take-up roller and rotation of this latter roller in a direction to wind thereon the tape from the other roller, reverses the withdrawal of the tape and permits its reuse. Such reversal may be accomplished so long as the tape is satisfactory for reuse.

In the device of Figs. 7 and 8 employing the guard or guide 21 adjacent the rolls 31, 32 and 33, and with the tape moving in the direction of the arrow in Fig. 8, the floating roll 32 and the lower roll 33 cooperate to remove hairs grasped therebetween. In this form when the tape has been exhausted, the operator can insert the stub shaft 21 on the knob 34 into the opening in the upper roller 28 and completely or partially rewind the tape onto this roller for reuse. After such rewinding, the stub shaft of the knob is removed and again inserted in the opening of the lower or take-up roller and the device is ready for operation in the manner explained above.

In the device of Figs. 1 to 4 inclusive, after the tape has been used, all that is required is for the operator to remove the stub shaft 17 of the rotatable knob 16, or the stub shaft 21 on the knob 20 if the construction of Fig. 6 is being employed, from the lower or take-up roller 8 and to insert this stub shaft into the opening of the upper roller 7 which was previously the feed or supply roller. Thereupon the roller 7 becomes the take-up roller and its manual rotation by the operator in a direction to wind thereon the tape, removes the tape from the roller 8. The tape in this latter operation is moved in a direction opposite to that previously mentioned. As shown in Fig. 4, when the roller 8 is the take-up roller, the tape moves in the direction of the arrow *a* and the hair is removed by engagement between the loose or floating roll 15 and the lower roll 12, and when the roller 7 is the take-up roller, the hairs are grasped between the loose or floating roll 15 and the upper roll 11 as the tape is then moved in the direction of the arrow *b*.

In view of the above remarks, it will be apparent that the present novel invention is highly effective in the removal of any unwanted or excess hairs from any part of the body. Furthermore, it will be evident that it is a simple matter to remove such hairs by placing the operative end of the device with the exposed adhesive surface of the tape against the surface of the body containing the hairs to be removed, rotating the knob whereby the hairs adhering to the adhesive on the tape are drawn between the loose or floating roll and the adjacent roll between which the tape passes upon rotation of the knob. When these hairs to be removed are securely grasped in this manner between the rolls, a quick pull or jerk on the device will remove such hairs quickly and effectively.

Having thus disclosed the invention, I claim:

1. A hair removing device for the extraction of superfluous hairs, comprising a supporting frame, a pair of rollers rotatably mounted in the frame, a coil of tape adapted to be fed from one of said rollers and received upon the other roller, and a plurality of spaced rolls over which the tape is drawn as it is fed from said one roller to the other and between which the hairs to be removed are grasped.

2. A hair removing device for the extraction of unwanted hairs from the face, arms or other parts of the body, comprising a supporting frame, a pair of rollers rotatably mounted in the frame and one of which is provided with a supply of adhesive tape and the other is adapted to

receive the adhesive tape from the first mentioned roller after it has been used, and a plurality of rolls disposed adjacent an end of the frame and over which the tape is fed to and from said rollers, said rolls being freely rotated and spaced apart an amount sufficient to allow the tape to pass between adjacent rolls and apply requisite tension to the tape whereby the hairs to be removed are drawn between adjacent rolls by the tape for removal.

3. A hair removing device for the removal of unwanted or superfluous hairs, comprising a pair of spaced plates providing a support, a coil of tape, a pair of rollers rotatably mounted between said plates one providing a feed roller and the other a take-up roller for the tape, and a plurality of coating rolls over which the tape passes from the feed to the take-up roller and between which are clamped the hairs to be removed as these hairs are drawn by the tape into the bite of the rolls as the rollers are rotated to move the tape.

4. A hair removing device for the removal of unwanted or superfluous hairs, comprising a support, a coil of adhesive tape rotatably mounted in the support, means for moving the tape, a plurality of freely rotatable rolls with the tape mounted to pass between the rolls and to be drawn thereover, one of said rolls being journaled in the support and another being free of the support and adapted to exert tension to the tape as it passes between said rolls, whereby when said rolls and tape are placed against the portion of the body from which the hairs are to be removed and the tape is drawn between the rolls, the tape carries along therewith and between the rolls the hairs to be removed and when the device is quickly pulled away from the body, the hairs grasped by the rolls and tape are removed.

5. A device for the quick and effective removal of unwanted or superfluous hair from the face, arms or other parts of the body, comprising a support, hair removal rotatable members carried by the support, a pair of rollers rotatably mounted in the support, a coil of adhesive tape having its opposite ends connected to said rollers and movable over the hair removal members with one of the rollers providing a tape supply roller and the other a take-up roller upon which the used tape is wound, means for rotating said rollers for supplying tape to the hair removal members, and means for reversing rotation of said rollers when the tape on the feed roller has been substantially exhausted whereby the previous supply roller thereupon becomes the take-up roller and the previous take-up roller thereupon becomes the supply roller and the tape is reused by the operator.

6. A device for the quick and effective removal of unwanted or superfluous hair from the face, arms or other parts of the body, comprising a support having spaced side walls, rotatable rolls provided at one end of the support and between the side walls, one of said rolls being offset with respect to the other rolls and free with respect to the support, a pair of rollers disposed between and journaled in the side plates, adhesive tape joined at its opposite ends to said rollers and

its intermediate portion passing over the rolls, and means for rotating the rollers whereby the tape may be drawn over the free roll and between it and the adjacent rolls and reused.

5 7. A hair removal device for the extraction of unwanted or superfluous hairs from the body, comprising a supporting frame, a pair of rolls rotatably mounted in spaced relation at one end of the frame, a freely rotatable and loosely positioned roll free of the frame and disposed forwardly of and intermediate said pair of rolls, adhesive tape carried by the frame and means for feeding the adhesive tape between the pair of rolls and over the loosely positioned roll whereby 10 the latter roll is carried by and applies tension to the tape as the tape is moved thereover.

15 8. A hair removal device for the extraction of unwanted hairs from the body, comprising a supporting frame, a plurality of rotatable and closely spaced rolls at one end of the frame with one 20 of said rolls being loosely positioned with respect to and free of the frame, and a pair of rollers spaced from said rolls and carrying a coil of adhesive tape adapted to be fed from one of the 25 rollers, over the loosely positioned roll and in contact with the other rolls and back to the other roller, whereby hairs to be removed are engaged by the adhesive tape over the loose roll and drawn into the bite between the last mentioned roll and an adjacent roll when the tape is 30 drawn thereover and extracted by a quick pull.

35 9. A device for the removal of unwanted or superfluous hairs, comprising a support, a feed roller provided with a coil of adhesive tape and a take-up roller for receiving the used tape, a plurality of freely rotatable members provided at one end of the support and including one or more members journaled in the support and a member free of the support and loosely positioned 40 with respect to the other member and movable relative thereto, the tape from said feed roller passing over the loose member and between said member and its adjacent member and back to the take-up roller, and means for rotating said take-up roller to withdraw tape from the feed roller when the tape about the loose member is placed over the hairs to be removed, whereby said hairs are drawn into and gripped between the adjacent members.

45 10. A hair removing device for the extraction of unwanted or superfluous hairs, comprising a supporting frame, a pair of rollers rotatably mounted in the frame, a coil of tape adapted to be fed from one of said rollers and received upon the other roller, a plurality of spaced rolls over which the tape is drawn as it is fed from said one roller to the other and between which rolls the hairs to be removed are grasped, and a guard adjacent the rolls for separating the hairs to remain from those to be extracted.
